UNITED STATES PATENT OFFICE.

ANDREW G. WASS, OF MINNEAPOLIS, MINNESOTA.

COMBINED LOCK BOLT AND JOINT PACKING STRIP FOR FRENCH DOORS.

1,407,966.

Specification of Letters Patent. Patented Feb. 28, 1922.

Application filed August 16, 1920. Serial No. 404,003.

To all whom it may concern:

Be it known that I, ANDREW G. WASS, a citizen of the United States, residing at Minneapolis, in the county of Hennepin and State of Minnesota, have invented certain new and useful Improvements in Combined Lock Bolts and Joint-Packing Strips for French Doors; and I do hereby declare the following to be a full, clear, and exact description of the invention, such as will enable others skilled in the art to which it appertains to make and use the same.

My invention has for its object to provide an exceedingly simple and highly efficient combined lock bolt and joint packing strip for French doors; and, to such ends, generally stated, it consists of the novel devices and combinations of devices hereinafter described and defined in the claims.

It is a well known fact that it is difficult to make tight joint strips which will entirely exclude both wind and water without much complexity.

The preferred form of this improved device is illustrated in the accompanying drawings, wherein like characters indicate like parts throughout the several views.

Referring to the drawings,

Fig. 1 is a front elevation of my improved combined lock bolt and joint strip mounted on one of a pair of French doors;

Fig. 2 is a vertical section taken on the line 2—2 of Fig. 1; with some parts broken away;

Fig. 3 is a horizontal section taken on the line 3—3 of Fig. 1, looking upwards; and

Fig. 4 is a vertical section taken on the line 4—4 of Fig. 1.

The numeral 5 indicates an ordinary French door on which my invention is mounted and 5^a an ordinary door casing on which said door is hinged. A lock bolt 6, having an operating handle 6^a, is held in operative position by outside guides 7 and 7^a fastened to the free end of said door, providing for free vertical movement of the bolt. The numeral 8 represents a joint packing strip or blade connected to said lock bolt 6 by means of a common sliding bar 9 to which both are secured by screw bolts 10, which engage in the threaded holes 11 of the bar. The said blade or plate 8, it will be noted is wider at its end portion where it is attached to the bar 9 and tapers therefrom to a considerably smaller width adjacent the

first guiding member 17 and from this point to the other side of the door is of uniform width. A recess 12 in the bottom of said door is provided in which said sliding parts are mounted.

A threshold plate 13, having an inclined packing shoulder 14 for engagement with said blade 8 and a bolt socket 15, is fastened to the threshold 16.

The packing blade 8 is guided by a series of U-shaped guide plates 17 inserted into the bottom of the door, secured thereto, and by flat end guide plates 18 fixed on the opposite door edges. A long guide strip 19, secured to the bottom of the door, co-operates with the guides 17 and 18.

Said lock bolt has a beveled nose 20 to make it easily engageable in its bolt socket. Likewise said blade 8 has rounded edges 21.

With the device described, the operation is probably obvious. When in an inoperative position, the friction of the several guide plates and the bolt guides is sufficient to hold said blade and bolt from dropping. To operate, the bolt 6 is thrust down into its locking socket carrying with it the blade 8 and camming the same against the inclined packing shoulder of the threshold, making said threshold absolutely wind-tight. The U-shaped guide plates 17, best seen in Fig. 4, guide said blade 8 and also provide a stop for said blade, when the lock is raised, by an upward thrust. The end guide plates 18 and the elongated guide strip 19 facilitate materially in this guiding action. The recess 12, cut out of the bottom of said door 5, allows said sliding parts to be mounted therein and provides the necessary clearance for their manipulation.

My invention may be, of course, applied to casement windows, ordinary doors, or any swinging sash and may be used vertically or horizontally with equal efficiency and simplicity wherever a wind-tight strip is needed in combination with a lock bolt.

What I claim is:

1. The combination with a door and threshold plate, of a lock bolt and joint packing blade mounted on the door and rigidly connected for common movements to simultaneously project said bolt and plate into operative positions, said blade having one end widened and said blade extending across the width of the door the widened end being secured to the bolt to enable the entire width

of the space between the threshold plate and the door to be packed by a manipulation of the bolt.

2. In a door lock and weatherstrip structure, a sliding bolt secured to the one side of the door adjacent its front lower edge, a bar attached to one side of said bolt adjacent the bottom thereof and disposed in a slot in said door, a blade rigidly secured to

said bar and also disposed in a slot in said door and extending from said bar across the width of said door and adapted to be moved with said bolt, a threshold block having a hole therein for receiving said bolt, and an inclined edge against which the said blade is adapted to wedge.

In testimony whereof I affix my signature.
ANDREW G. WASS.
